CLAIM

The ornamental design for opener for pop-top containers, substantially as shown and described.

DESCRIPTION

FIG. 1 is a top perspective view of an opener for pop-top containers showing my new design;

FIG. 2 is a bottom perspective view thereof;

FIG. 3 is a bottom elevation thereof;

FIG. 4 is a top elevation thereof;

FIG. 5 is a side elevation of the view in FIG. 3;

FIG. 6 is an end elevation view of the left side of FIG. 5; and

FIG. 7 is an end elevation from the right side of FIG. 5.
